ANTENNA FOR TELEVISION RECEIVERS

Edward Finkel, Great Neck, N. Y., assignor to JFD Manufacturing Co., Inc., Brooklyn, N. Y., a corporation of New York

Application January 8, 1957, Serial No. 44,443

Term of patent 14 years

(Cl. D26—14)

Fig. 1 is a front perspective view of an antenna for television receivers, showing my new design with the telescopic dipoles in closed position;

Fig. 2 is a front perspective view thereof, to a reduced scale, with the telescopic dipoles extended and one dipole rotated; and

Fig. 3 is a diametrical cross-sectional view of the control knob thereof.

The dotted line showing of numerals in Fig. 1 of the drawing is for illustrative purposes only, omission thereof in Fig. 2 being for convenience in illustration. The rear of the device is substantially plain.

I claim:

The ornamental design for an antenna for television receivers, as shown and described.
